UNITED STATES PATENT OFFICE.

CHAUNCEY C. WOODWORTH, OF ROCHESTER, NEW YORK.

DESIGN FOR BOTTLES.

Specification forming part of Design No. 7,836, dated November 3, 1874; application filed October 24, 1874.
[Term of Patent 3½ years.]

To all whom it may concern:

Be it known that I, CHAUNCEY C. WOODWORTH, of the city of Rochester, in the county of Monroe and State of New York, have invented a new and original Design in Bottles; and I do hereby declare that the following is a full, clear, and exact description of the same, reference being had to the accompanying drawings, in which—

Figure 1 is a perspective view. Fig. 2 is a rear view.

My invention consists of a bottle in the form of a female bust, with the shoulders and back made in three angular planes, which converge to the pedestal in wedge shape, to form the body of the bottle, as hereinafter described.

In the drawings, *a* represents the bust. *b* is the head, surmounted by the ordinary bottle neck or nozzle *d*. *c* is the pedestal. *ff* is the draping. *e* is the hair, which is represented as flowing loosely over the back of the figure. *g g* represent the shoulders, and *h* the back. These parts form plain or straight surfaces,

which extend down in angular form to the pedestal, and thus give the body of the bottle a wedge shape at the rear and sides, while the front presents the full width and form of a female bust. This angular form of the shoulders and back forms the essential feature of my design.

This bottle is intended specially for holding perfumery and hair-oils.

Having thus described my invention, what I claim as new is—

The design for a bottle, in the form of a female bust, with the plain angles *g g h* at the shoulders and back converging to the pedestal, as shown and described.

In witness whereof I have hereunto signed my name in the presence of two subscribing witnesses.

CHAUNCEY C. WOODWORTH.

Witnesses:

EDWIN B. SCOTT,
R. F. OSGOOD.
